UNITED STATES PATENT OFFICE

90,626

DESIGN FOR A TEXTILE FABRIC

Edward G. Meyers, Maplewood, N. J., assignor to
M. C. D. Borden & Sons, Inc., New York,
N. Y., a corporation of New York

Application April 1, 1933. Serial No. 47,660

Term of patent 7 years

To all whom it may concern:

Be it known that I, EDWARD G. MEYERS, a citizen of the United States of America, and residing at Maplewood, in the county of Orange and State of New Jersey, have invented a new, original, and ornamental Design for Textile Fabric, of which the following is a specification, reference being had to the accompanying drawing, forming part thereof.

The figure in the drawing in a plan view in full size showing the details of the design.

I claim:

The ornamental design for a textile fabric substantially as shown.

EDWARD G. MEYERS.
